Attorneys

UNITED STATES PATENT OFFICE.

JAMES J. LAWLER, OF MOUNT VERNON, NEW YORK.

THERMORADIATOR TRAP.

Application filed July 24, 1924. Serial No. 722,068.

To all whom it may concern:

Be it known that I, JAMES J. LAWLER, a citizen of the United States of America, residing at Mount Vernon, in the county of Westchester and State of New York, have invented certain new and useful Improvements in Thermo-radiator Traps, of which the following is a specification.

This invention relates to new and useful improvements in thermo-radiator traps.

The primary object of the invention is to provide a radiator trap which will insure economy in the consumption of fuel and will allow the radiating surface to operate to its full capacity and efficiency.

A further object of the invention is to provide a trap for steam heated radiators, or other heating units, which will automatically remove air and water of condensation, by thermostatic action, and at the same time prevent the escape of live steam from the heating unit.

Other objects and advantages of the invention will be apparent during the course of the following description.

In the accompanying drawing forming a part of this specification and in which like numerals are employed to designate like parts throughout the same,

Figure 1 illustrates in elevation a steam heated radiator with its supply and return pipes, shown in dotted lines, and with the improved trap embodying this invention shown in full lines as operatively connected thereto,

Figure 2 is a central vertical sectional view of the trap embodying this invention and shows the valve portion of the same in its opened position, and

Figure 3 is a fragmentary view of a portion of the structure illustrated in Fig. 2 and shows the valve in its closed position.

In the drawing, wherein for the purpose of illustration is shown a preferred embodiment of this invention, the numeral 5 designates a sectional radiator which is to be heated by steam fed thereto through the pipe 6 having a controlled connection with any portion of one end radiator section, the control consisting of any suitable type of valve 7. The opposite end section of this radiator 5 is provided, in close proximity to its lower end, with a discharge opening to which is attached the thermo-radiator trap, embodying this invention and designated in its entirety by the numeral 9. This radiator

trap 9 is also connected to the return pipe 10, which leads from the radiator 5 to the source of heat or the steam generator.

The thermo-radiator trap embodying this invention includes a casing consisting of the hollow body portion 11 having an externally threaded connection 12 to which is attached the flanged end 13 of the nipple 14 having a threaded end 15 adapted to be attached to the radiator, illustrated in Fig. 1, the said nipple 14 being wedged against the outer tapered end of the connection 12, for preventing leakage at this joint, by the nut 16. This casing 11 is provided with an open upper end 17 which is internally screw-threaded for connection with the removable cap 18, as best illustrated in Fig. 2.

In Fig. 2, the casing 11 is illustrated as being provided with an annular water pocket 19 employed for trapping water of condensation. It will be seen that this annular water pocket is formed by the lower portion of the wall of the body portion 11 and the annular partition 20 which forms a cylindrically-shaped well 21. The bottom wall 21 of this well 21 is provided with an axially positioned opening 22 having a valve seat 23 formed at its inner end. Communicating with this opening 22 is an internally screw-threaded connection 24 to which is adapted to be connected the return pipe 10, best illustrated in Fig. 1.

It will be seen that the location of the annular water pocket 19 in respect to the nipple 14 and the lower ends of the sections forming the radiator 5 will permit the said sections to drain into this pocket. The annular partition 20 will also insure the pocketing or trapping of a predetermined amount of water of condensation in the pocket 19.

The cap 18 is illustrated as being provided with a depending tubular boss 25 within the bore of which is loosely positioned an adjusting nut 26 which is threadedly connected to the reduced portion 27 of the upper part 28 of a two-part valve stem. This upper part 28 is provided with a depending boss 29 which cooperates with the boss 30, carried by the lower part 31 of the two-part valve stem for limiting the relative movement between the parts 28 and 31 of this valve stem and also limits the movement of the valve 32 away from its valve seat 23. It will also be seen that the distance of opening of this valve 32 may be varied by adjusting the cap 26 upon the re-

duced threaded portion 27 of the upper valve stem part 28. A closed chamber 33 is provided for carrying a desired amount of volatile liquid 34 and has its upper wall, which is constructed in the form of a corrugated diaphragm 35, connected to the upper part 28 of the valve stem, while the body portion of this closed chamber 33 is suitably connected to the lower part 31 of the valve stem, as best illustrated in Figs. 2 and 3. It will be seen, by inspecting Fig. 2, that this closed chamber 33 is provided with an annular depending extension 35^a which dips into the water of condensation trapped in the annular water pocket 19 for the purpose of causing the temperature of the water of condensation to influence the volatile liquid 34 housed within the chamber 33.

By inspecting Figs. 2 and 3, it will be seen that the lower part 31 of the two-part valve stem is formed in two sections which are threadedly connected at 36 and are constructed in this manner for permitting the renewal of the valve portion 32 should the same become pitted or damaged in any way.

Received within the well 21 and engaging the bottom wall 21^a of the same and the body portion of the closed chamber 33 is a spring 37 which operates to normally retain the valve 32 in its opened or unseated position.

The operation of this thermo-radiator trap may be described as follows:

When the apparatus is properly adjusted for operation, the spring 37 will normally retain the valve 32 in its opened or unseated position. The heating of the volatile liquid 34 within the closed chamber 33 will cause the former to expand and this expansion will cause the valve 32 to be forced against its seat 23. Should the volatile liquid 34 be again cooled, by any means, the volatile liquid will condense and permit the spring 37 to dominate for again unseating the valve 32.

When live steam starts to enter the sectional radiator 5, through the steam pipe 6 and by the valve 7, the water of condensation and air within the various sections of the radiator will start to flow therefrom through the nipple 14, into the trap 9. The volatile liquid 34, being in a cooled or thoroughly condensed state, the valve 32 will of course be in its opened or unseated position and the water of condensation will flow into the pocket 19 until this is filled and will then overflow into the well 21 from whence it will be discharged into the return pipe 10 through the opening 22, the air being carried off in the same manner. This action continues allowing air and condensation to escape through the return pipe until the condensation rises in temperature to a few degrees below the temperature of

steam at atmospheric pressure. When the condensation arrives at this temperature, it radiates its heat to the volatile liquid in the closed chamber 33, causing the same to form into a gas and thus exerting a pressure on the diaphragm 35 which results in forcing the valve 32 on its seat. As condensation of a slightly lower temperature finds its way to the trap it radiates its lower temperature to the volatile liquid which quickly condenses and allows the spring 37 to lift the valve 32 whereupon the radiator will be relieved of condensation.

It is now believed that the construction and operation of this thermo-radiator trap will be understood from the above detail description and that no further explanation is deemed necessary.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:—

1. In a device of the type described, a casing having an inlet and an outlet, a well formed in said casing communicating with said outlet, a valve for controlling said outlet, an annular water pocket surrounding said well and overflowing thereinto, an expandable chamber operatively connected to said valve and having an annular extension depending into said water pocket for controlling the operation of the valve, and means for normally retaining said valve open.

2. In a device of the type described, a casing having an inlet and an outlet, a well formed in said casing communicating with the outlet and located below the inlet, a valve for the outlet having a two-part stem, a water pocket in said casing below said inlet and overflowing into said well, an expandable chamber connecting the parts of said stem and projecting into said water pocket, and means for normally retaining said valve unseated.

3. In a device of the type described, a casing having an inlet and an outlet, a well formed in said casing communicating with the outlet and located below the inlet, a valve for the outlet having a two-part stem, a water pocket in said casing below said inlet and overflowing into said well, an expandable chamber connecting the parts of said stem and depending into said water pocket, means for normally retaining said valve unseated, and means for limiting the distance to which said valve may be opened.

In testimony whereof I affix my signature.

JAMES J. LAWLER.
